DRUM USED IN THE PROCESSING OF HIDES
AND SKINSNorman Dwight Clarke, Barrie, Ontario, Canada,
assignor to Clarke & Clarke Company, Limited,
Barrie, Ontario, Canada

Application November 27, 1936, Serial No. 113,068

4 Claims. (Cl. 149—11)

This invention relates to a drum used in the processing of hides and skins of the rotary type, and the features of the invention are in the method of securing the gudgeon plate, journal 5 and driving gear on the exterior of the head of the drum.

It is the common practice to secure the gudgeon plate and gears on the head of the drum by fastening bolts, and having the heads of the 10 bolts on the inside of the drum.

Where the gudgeon plate and gears are secured by this method and from the nature of the liquid contents of the drum, there is a tendency of decay and wear of the wood around the 15 bolt holes, and loosening of the fastenings, to cause frequent repairs and adjustments.

Further, where bolts are used for fastenings, and the heads project from the inner face of the head of the drum, there is a tendency to scratch and abrade the soft face of the hides and skins when being tumbled about in the drum while being processed by the action of the rotation of the drum.

The object of the invention is to secure the 25 gudgeon plate and gears to the exterior of the head of the drum without any of the fastenings passing through the drum head, and with fastening means adapted to rigidly secure the parts in position, and readily adjusted to tighten up, 30 and centre accordingly with the natural shrinkage and expansion of the wood itself caused by the variance in temperature and the nature of the liquid contents of the solutions used.

In the hereunto annexed drawing:—

Figure 1 is an end elevational view of the 35 drum; and

Figure 2 is a detail sectional view on lines 2—2, Figure 1.

Like letters of reference refer to like parts 40 throughout the drawing.

Referring to the drawing A, designates the staves and B, the head of a standard circular tanning drum, bound and held together by hoops D, the drum being rotatably mounted on end 45 standards C, as shown in dotted lines in Figure 1, of the drawing.

E, designates a gudgeon plate preferably round, and having centrally formed therewith is a bearing F, adapted to seat in a pillow-block 50 G, set on the standard C. Formed through the centre of the bearing F, is a bore H, into which a tubular connection may be fitted to allow and force the liquids into the drum.

Formed on the outer face of the gudgeon plate 55 E, at regular intervals are a series of stay-blocks

I, having a countersunk centrally disposed pocket J, to receive the fastening nut K, on the end of a tension rod L, which extends radially therefrom and out through the stave A, and keeper M, on the outer face of the stave, and secured by fastening and adjusting nuts N and Y, the nut N, being on the outer end of the rod, and the nut Y, engaging against the inner face of the stave.

The keeper fitted on the outer face and at 10 each end of the stave A, is maintained in position by a tie rod O, on the ends of which are adjusting nuts P.

The tension rods L, of which there may be 15 any plurality, accordingly with the size of the drum, extend out through a bore Q formed through the outer face of the block I, in radial relation to project through the outer periphery of the drum; by which the gudgeon plate E, may be centrally maintained against the head of the drum, so that adjustments may be made to centre and maintain rigidity by turning the nuts N and Y, on the outer ends of the rods L.

Mounted on and supported by the tension rods 20 L, is an internal gear R, by which the drum is rotated by the engagement with a pinion gear and motive connection or any suitable power means.

The pinion gear and the motive means, I 25 have not illustrated in mesh with the internal gear as it does not embody any feature of my invention. One of the essential features is the internal gear R, the method of mounting it on the tension rods L, and the means for maintaining and adjusting to a true centre.

Formed integral around the outer periphery of the internal gear R, at regular intervals to 30 register with the radial disposition of the tension rods L, are ears S. Bolted to the underside of the ears S, are stay-blocks T, having a central bore through which the tension rods L, pass to carry the internal gear R.

While I have shown as a part of the rotating 35 mechanism, an internal gear R, mounted on the tension rods L, any other form of gear may be equally adapted for the purpose. The internal gear may also be readily removed where other drive mechanisms are to be used.

V, designates an adjusting nut on the tension 40 rod L, adapted to engage against the outer face of the stay-block T, to centrally adjust the internal gear R, and to retain it in position, firm and rigidly with the head of the drum, and without any fastening connection with the head of the 45 50 55

drum proper, that is extending into, or through the wooden structure of the head.

What I claim as new and desire to file by Letters Patent is—

- 5 1. In a drum of the character specified, the combination with the head of the drum, a gudgeon plate and bearing formed therewith, a series of tension rods extending radially therefrom, said rods projecting through the outer periphery of the said drum with fastening nuts on the ends thereof for maintaining and centrally adjusting the said gudgeon plate.
- 10 2. In a drum of the character specified, the combination with the head of the drum, a gudgeon plate and bearing formed therewith, a series of stay blocks formed at regular intervals around the outer face of said gudgeon plate, a series of tension rods extending in radial relation from the said stay-blocks, the ends of said tension rods projecting through the outer periphery of said drum, keepers and fastening nuts fitted on the ends of said rods, for maintaining and centrally adjusting the said gudgeon plate with the head of the drum.
- 15 3. In a drum of the character specified, the combination with the head of the drum, a gudgeon plate and bearing formed therewith, a series of stay blocks formed at regular intervals around

the outer face of said gudgeon plate, a series of tension rods fitted into said stay blocks, said tension rods extending in radial relation from said stay blocks, the ends of said tension rods projecting through the outer periphery of said drum, keepers and fastening nuts fitted on the ends of said rods for maintaining and centrally adjusting the said gudgeon plate with the head of the drum. 5

4. In a drum of the character specified, the combination with the head of the drum, a gudgeon plate and bearing formed therewith, a series of stay blocks formed at regular intervals around the outer face of said gudgeon plate, a series of tension rods fitted into the said stay blocks and extending in radial relation therefrom, the ends of said tension rods projecting through the outer periphery of said drum, keepers and fastening nuts fitted on the ends of said rods for maintaining and centrally adjusting the said gudgeon plate with the exterior head of the drum, an internal gear 10 concentrically mounted on said tension rods, stay blocks fitted with the said gear, said tension rods passing through said stay-blocks, adjusting nuts fitted on said tension rods adjacent with the said stay-blocks for maintaining and centrally 15 adjusting said internal gear.

NORMAN D. CLARKE.
